JAMES S. ELDER AND HERBERT J. WILSON, OF FORT COLLINS, COLORADO.

INTERLOCKING REVERSIBLE FEED-TROUGH.

1,228,421.

Specification of Letters Patent.

Patented June 5, 1917.

Application filed February 27, 1917. Serial No. 151,235.

To all whom it may concern:

Be it known that we, JAMES S. ELDER and HERBERT J. WILSON, citizens of the United States, both residing at Fort Collins, in the county of Larimer and State of Colorado, have invented a new and useful Improvement 5 in Interlocking Reversible Feed-Troughs, of which the following is a specification.

Our invention relates to improvements in feeding troughs for use especially in the feeding of sheep where a large number of troughs must be provided and where it is necessary or advisable to reverse or dump 10 the troughs after each feeding. The objects of the improvement are to provide simple and substantial reversible dump troughs that may be arranged in series so as to be easily accessible and all of the troughs in a 15 series operatively interlocked so as to be easily and quickly reversed or dumped in unison by one operation; also to provide co-operating or interlocking means that will positively and easily dump all of the troughs 20 in a series in unison; also to arrange the interlocking means in position where it will not obstruct free access to or about the troughs. We attain these objects by the 25 construction illustrated in the accompanying drawing which forms a part of this specification.

In the drawing, Figure 1 is a perspective view of a series of reversible feed troughs constructed and interlocked according to our 30 invention. Fig. 2 is a side view of such a series. Fig. 3 is a detail of an end plate and axle. Fig. 4 is a detail of a drive pulley, the upper half being in elevation and the lower half in cross section. Fig. 5 is a detailed 35 view of the operating handle and pulley and cable anchoring means. Fig. 6 is an end view of a feed trough removed from the supporting framework. Fig. 7 indicates a 40 manner of anchoring the operating cable to a drive pulley.

The same reference numerals throughout the several figures indicate the same or like 45 parts.

1 are reversible feed troughs having axles 50 at their ends and revolvably mounted in suitable framework. As shown, such framework consists of posts 2 and 3 set in the ground and braced by cross pieces 4 above the troughs. If desired the posts may be set in 55 concrete as indicated at 5.

Any desired or convenient number of troughs for the feeding pen are to be thus mounted and arranged parallel to each other in a series as shown in Figs. 1 and 2, sufficient room being provided between troughs 60 for easy access. The supporting posts of the several troughs in a series may be braced and held rigid by braces or railing 6. The posts upon which railing 6 is fastened are to be long enough so that the railing is lifted 65 well above the ground and out of the way. When the posts are set firmly in the ground the brace railing 6 may not be necessary, or necessary only between posts at one end of the troughs, as shown in a drawing. 70 Thus if the braces or railing 6 is fastened to posts 2 the other supporting posts 3 need be only high enough to support cross pieces 4.

If for any reason the setting of the posts in the ground is not feasible or desired, it 75 is obvious that other means of constructing a rigid framework for a series of troughs may be employed.

Axle 7 at one end of each trough is rigidly anchored to the end of the trough by 80 means of plate 8, and these axles are adapted to extend through holes in the posts 2 and have squared and threaded outer ends upon, which drive pulleys 9 are anchored. 10 are double grooved idler pulleys mounted on the 85 framework above each drive pulley.

The several troughs in a series are connected or interlocked by means of a continuous operating cable 11 arranged over and around the idler and drive pulleys in such 90 manner that the movement of the cable will revolve and dump all of the troughs in unison; and the portions of cable 11 extending longitudinally of the series are held taut and well above the ground and out of the 95 way. The manner of arranging the cable is shown in Figs. 1 and 2, as follows: Starting, for example, at the top and in one groove of the idler pulley 10 at the extreme right end of the series shown, the cable extends in anti-clockwise direction over that idler and is looped downward and clockwise around drive pulley 9, upward across and again over the idler pulley in anti-clockwise direction in the other groove, then to 100 the left to and over the idler pulley at the next trough, down around the corresponding drive pulley, and upward across and again over that idler, and thus on in like manner throughout the series. From the 110

last idler the cable extends back along the series to the starting point.

In order to insure positive operation the cable may be anchored to each drive pulley 9 by suitable clamps 16.

To operate the cable we provide a crank 12 upon one of the idler pulleys, as for example, at one end of the series, where it is most convenient. Suitable means may 10 be provided whereby the cable may be anchored in any desired position thus holding the troughs either in upright or reversed position. A simple contrivance to 15 effect the anchoring of the cable is indicated in Fig. 5 where the idler 10 upon which the crank 12 is fastened is anchored to its shaft 13. Shaft 13 extends through the post 2 and has a perforated disk 14 on 20 the opposite end. Holes are bored in that post 2 to receive a pin 15 inserted through a hole in disk 14.

In operation, the troughs, when in upright position as shown in Figs. 1 and 2, are used in the ordinary manner for feeding 25 sheep. After each feeding the troughs are reversed or dumped to remove all waste and foreign matter and keep the troughs open and clean for the next feeding. This is easily and quickly done by operating the 30 cable; the locking pin 15 is removed and crank 12 turned in clockwise direction moving the cable in the direction of the arrows in Fig. 2, turning all of the troughs on their axes one-half revolution dumping them and placing them in a reversed position. The 35 pin 15 is then inserted so as to lock the cable and troughs in that position until time for the next feeding, when the troughs are

again turned in upright position by a reverse movement of the cable.

40

We claim:

1. The combination of a series of feed troughs reversibly mounted upon axles in a framework, drive pulleys anchored to an axle of each trough, idler pulleys mounted 45 on said framework above each drive pulley, a continuous cable passing around and operatively connecting all of said drive pulleys throughout the series and arranged to pass over said idler pulleys so that the portions of said cable extending between troughs longitudinally of the series are held well above the level of the troughs to allow 50 free access thereto, with means to operate said cable to reverse said troughs in unison, substantially as described.

2. The combination of a series of reversible feed troughs arranged parallel to each other and mounted between posts, a drive pulley anchored to one end of each trough 60 and arranged to receive an operating cable, idler pulleys mounted upon said posts above each drive pulley, a continuous operating cable arranged over said idler pulleys throughout the series so as to be held well 65 above the ground and looping from each idler pulley down and around the corresponding drive pulley, with means to operate said cable to reverse the troughs in unison, substantially as described.

JAMES S. ELDER.
HERBERT J. WILSON.
